ELECTRIC PIANO

Harold B. Rhodes, 2443 Greenbriar St., Anaheim, Calif., assignor, by mesne assignments, of one-half to Fender-Rhodes, Inc., Fullerton, Calif., a corporation of California

Filed June 18, 1964, Ser. No. 80,470

Term of patent 14 years

(Cl. D56—9)

FIG-3

FIG-4

FIG-5

FIG-6

FIGURE 1 is a front perspective view of an electric piano embodying my new design;

FIGURE 2 is a rear elevational view on a reduced scale;

FIGURE 3 is a top plan view on a reduced scale;

FIGURE 4 is a front elevational view on a reduced scale;

FIGURE 5 is a side elevational view looking from the left of FIGURE 4; and

FIGURE 6 is a side elevational view looking from the right of FIGURE 4.

The bottom of the electric piano is substantially plain. The dominant features of the design reside in the portions shown in solid lines.

I claim:

The ornamental design for an electric piano, substantially as shown and described.
